(57) **CLAIM**

The ornamental design for a front fender for a vehicle, as shown and described.

DESCRIPTION

This application contains subject matter related to the following co-pending U.S. design patent applications:
Application Ser. No. 29/694,271, filed Jun. 10, 2019 and entitled “Front Fender for a Vehicle”;
Application Ser. No. 29/725,348, filed Feb. 25, 2020 and entitled “Front Fender for a Vehicle”; and
Application Ser. No. 29/747,493, filed herewith and entitled “Vehicle, Toy, and/or Replicas Thereof”.

FIG. 1 is a front view of a front fender for a vehicle according to the design;

FIG. 2 is a left, front perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

1 Claim, 8 Drawing Sheets
